SELF-FEEDING MAGAZINE PENCIL

Joseph F. Dredge, Highland Park, Mich.

Application January 22, 1935, Serial No. 2,947

1 Claim. (Cl. 120—19)

My invention relates generally to magazine pencils, and particularly to a self-feeding magazine pencil which is composed of few and simple parts and is capable of being manufactured at a relatively low cost, and an important object of my invention is to provide a mechanically efficient magazine pencil of the character indicated above which will not readily get out of order, and in which the individual leads contained in the magazine thereof are fed automatically into place for use in the pencil.

Other important objects of my invention will be apparent from a reading of the following description in connection with the drawing, wherefore in for purposes of illustration I have shown a preferred embodiment of my invention.

In the drawing:—

Figure 1 is a general side elevational view of the embodiment.

20 Figure 2 is a vertical longitudinal sectional view taken through Figure 1 approximately centrally.

Figure 3 is a vertical longitudinal sectional view taken through the extensible part of the pencil.

Figure 4 is a longitudinal sectional view similar to Figure 3 taken at right angles thereto.

Figure 5 is a plan view of one of the lead gripping members.

30 Figure 6 is an edge elevational view of Figure 5.

Figures 7, 8, 9 and 10 are transverse vertical sectional views taken through Figure 2 approximately on the lines 7—7, 8—8, 9—9, and 10—10, respectively.

35 Figure 11 is a perspective view of the tensioning spring and feeder.

Figure 12 is a longitudinal sectional view through the eraser cap.

Figure 13 is a horizontal sectional view 40 through another embodiment in which the lead guiding bore is of a polygonal instead of a circular shape, so as to handle square or polygonal leads as well as round leads.

45 Referring in detail to the drawing, the numeral 5 refers generally to the embodiment which is composed of the tubular handle 6 having the slits 7 at one end and the slits 8 at the opposite end to provide for expansion of these ends and enable the portions defined between the slits to be contracted so as to grip members inserted in the respective ends.

50 Into the end equipped with the slits 8 there is forced a metallic cup 9 containing an eraser 10, the cup 9 being held in place by friction. At the same end of the handle 6 and longitudinally dis-

posed is a pocket clip 11 which is fastened in place by means of an anchor 12 which traverses the handle as indicated in Figure 2 and provides a pivot for a tensioning and feeding plunger to be described.

55 Slidably telescoped into the opposite end of the handle 6 is the lead feeding section 13 which is in the form of a tube having open ends one of which is slidably telescoped into the handle 6, the remaining end extending from the handle as shown in Figures 1 and 2.

The tube 13 constitutes the means for holding in opposed relation two wooden or other suitable material half-round members 14 and 15 which are substantially identical in structure and which form the actual guides for the lead, define the lead magazine, and the writing point of the pencil. At one end of the members 14 and 15 there is a frustro-conical enlargement 16 defining a shoulder 17 arranged to abut the outer end of the tube 13 as shown in Figures 2, 3 and 4, while the balance of the members is snugly received within the tube 13 so as to be forcibly engaged in face to face relation as indicated in Figures 2, 3 and 4 and also in the cross sectional Figures 7, 8, 9, and 10. The inner ends of the half sections 14 and 15 are arranged approximately flush with the inner end of the tube 13 as indicated in the drawing.

Each of the sections 14 and 15 is provided in its flat side with a longitudinal half bore which is either half round or of the composite shape indicated in Figure 13 for the purpose of receiving either round or polygonal shaped leads, the two-half bores forming the complete lead guiding bore when the sections are opposed and in position in the tube 13.

One side of the bore 18 and the corresponding side or edge of the section is slightly cut away from the point 19 to the point 20 as indicated at 40 21 and the opposite side of the flat face of the section is similarly reduced as indicated at 22 beginning from the point 23 and extending to the inner end of the section. The cut-away parts 21 provide when the sections are opposed and 45 in assembled position, the slideway for the spring plunger which is generally designated 24, the slideway being narrower than the lead. The

cut-away portions 22 provide the lead receptacle or magazine which is closed by the inner side of the tube 13 which surrounds the space defined by the cuts 21 and the edge of the plunger in the slideway. It will be noticed that the end of the cuts 22 which is defined by the point 23 is outward of the point 19.

The individual leads 25 which, as stated, may be either round or polygonal in shape, rest in the space defined by the cuts 22, 22 as shown in Figure 7 and are confined laterally by the tube 13 and at their ends by the portions 19 and 20 of the sections 14 and 15, and by the edge of the plunger.

The long flat spring plunger 24 has a journal 26 at its inward end which is pivoted on the pivot 12 in the handle 6, the plunger being of a length 10 to extend well into the tube 13 through the slot which is defined by the cut-out portions 22, 22 in the sections 14 and 15 as shown in Figure 2, so that the outer end of the spring 24 can reach 15 the point 23, and in so doing pass outwardly of the point 19 when the tube 13 is telescoped into the handle 6. When positioned, as shown in Figure 7, in the lead guiding bore, the upper edge of the plunger 24 prevents a lead from falling 20 from the magazine into the lead guiding bore 18, but when the plunger is withdrawn to a position inward of the point 20, which is the inward end of the magazine, a lead is free to drop from the magazine into the lead guiding bore, is in 25 such a position that when the tube 13 is pushed into the handle 6 from the extreme extended position in which the plunger was withdrawn and a lead permitted to fall into position in the bore, the plunger will get behind the inner end of the new lead and push the same in an outward direction.

It is to be observed that a new lead is fed into the lead guiding bore without removing the old lead or a worn down portion thereof and without disturbing the worn down lead, which can be seen in position in Figure 2, with the new lead 35 therebehind.

The plunger 24 is of spring character so as to strengthen the relationship of the parts with 40 which it is associated and at the same time provide for a desirable amount of flexible relation between the parts which would be absent if a rigid feeding member were to be employed. It will be observed that the pencil is formed of only 45 the following parts, the tubular handle, the spring plunger 24, the tube 13, and the two sections 14 and 15. Although the pocket clip 11 and the eraser are not the essential parts of the invention apart from the use and manipulation 50 of the invention as a magazine pencil, it will be observed that the member 12 which holds the pocket clip 11 serves also as the pivotal mounting for the spring 24, and that the pivot 12 and the journal of the spring 24 form the abutment 55 for limiting the inward socketing movement of the cup 9 which contains the eraser 10. Therefore, real cooperation is thought to be present between the pocket clip and the eraser structure and the handle tube 6 and the spring 24.

It will be observed that the slot in which the lead feeding plunger 24 works and which is defined by the opposed cut out portions 21 is narrower than the lead receiving bore 18, so that the leads are not permitted to fall through the 5 said slot but stop in the said bore when the support of the upper edge of the plunger is withdrawn from that part of the slot which is in communication with the lead magazine. The relative lengths of the tubes and of the sections 10 14 and 15 are such that the tube 6 may be withdrawn in an axially outward direction a sufficient distance to completely withdraw the plunger 24 from closure relation to the lead magazine without coming off the tube 13. The tubes 6 and 15 13 and also the body composed of the sections 14 and 15 may have shapes and contours other than circular, and these parts may be constructed from different suitable materials.

It is obvious that when the feed plunger has 20 been pushed all of the way in its inner end will substantially abut the shoulder 23 so that the axially inward end of the full-length lead 25 will be flush with the shoulder 23 and completely out of the way of a following lead which is 25 free to drop from the magazine cut, the bore 18 to act as a plunger for pushing the said full lead outwardly when the plunger 24 is worked inwardly after the said following lead has dropped from the magazine into the bore 18.

Although I have shown and described herein a preferred embodiment of my invention, it is to be definitely understood that I do not desire to limit the application of the invention thereto, and any change or changes may be made in the 35 materials, and in the structure and arrangement of the parts, within the spirit of the invention and the scope of the subjoined claim.

What is claimed is:—

A self feeding magazine lead pencil of the class 40 described comprising a handle, an operating tube telescoped in said handle, a pair of juxtaposed half round members in said tube, said members being provided with registering semi-circular longitudinally extending grooves therein defining 45 a lead receiving and guiding bore, the intermediate portion of the adjacent sides of said members being cut away above the bore defining a magazine chamber for communicating the lead from the magazine into said bore, the adjacent side 50 of the members being cut away below the bore for a lead feed plunger which is slidable therein between said members and in said bore and having one end secured to said handle, and an abutment between said members adjacent the outer 55 ends thereof for limiting the outward movement of said plunger.

JOSEPH F. DREDGE.
